UNITED STATES PATENT OFFICE.

OSKAR SÖRGEL, OF BIESERN, NEAR ROCHLITZ, GERMANY.

MACHINE FOR MANUFACTURING ADHESIVE INSECT-TRAPS.

1,196,821.

Specification of Letters Patent.

Patented Sept. 5, 1916.

Application filed February 24, 1914. Serial No. 820,604.

To all whom it may concern:

Be it known that I, OSKAR SÖRGEL, a citizen of the German Empire, residing at Biesern, near Rochlitz, in Germany, have invented certain new and useful Improvements in Machines for Manufacturing Adhesive Insect-Traps, of which the following is a specification.

One method of manufacturing adhesive insect-traps, commonly called fly-papers, consists in passing a strip of paper over a cylinder or drum coated with adhesive, the drum having a transverse channel or channels, so that gaps are produced in the coating of adhesive applied to the strip. The strip is then commonly cut into sheets by hand, and tabs or eyes are attached to the sheets, at the edges free from adhesive, whereupon the sheets are rolled up singly, in order to be placed in packing tubes. These latter operations, performed by hand, require a considerable number of operatives, and the object of the present invention is to provide a machine for performing them in a more expeditious and economical manner.

The invention is illustrated in the accompanying drawings, in which—

Figure 1 is a plan view of a portion of the machine, Fig. 2 a side elevation, and Fig. 3 an end elevation, viewed from the left-hand side of Fig. 1. Fig. 4 is a plan view showing a portion of the machine not shown in Fig. 1. Fig. 5 is a section, showing part of the machine drawn to a larger scale.

In the drawings, 1 designates a table, on to which is fed the strip of paper 2, coated with adhesive in the manner described. At the inner end of the table there is a vertical frame 3, on which slides a U-shaped member 4, supported by springs 4^a and carrying a plate 5 mounted to rock on a horizontal shaft 10. This plate 5 normally lies parallel under a horizontal plate 6 fixed to the frame 3, and has on its upper surface a few short pins or spikes, whereby it is enabled to grip the front edge of a strip of paper 9 fed step by step between the plates 5 and 6. The paper strip 9 is fed between the plates by feed rollers 7 and 8 and carries adhesive eye-tabs 9^a to be applied to the fly-paper. The portion of the strip 9 between the plates

is cut off by a knife 13. The shaft 10 has cogs 11, which during the descent of the member 4 and plate 5 coat with cogs 12, fixed to the frame 3, so that the plate 5 is rotated, so that the portion of paper cut off from the strip 9 and attached to the plate 5 comes to lie face downward, and is then pressed on to the fly-paper strip 2 on the table 1. The member 4 is moved downward by means of the main actuating shaft 14, to which are fixed two mutilated toothed wheels 15 meshing with racks 15^a formed on the member 4. The tabs consisting of small sheets of paper cut from the strip 9 are applied to those portions of the strip 2 which are not coated with adhesive when the strip 2 is introduced into the machine. For attaching the eyes, glue is applied to the strip 2 by a brush 16, before the member 4 has completed its descent. The brush 16 dips into a heated glue-container 17, and has a curved shank 18 resting, near the brush, on a roller 19. The shank has an inclined part, near the roller 19, joined to a horizontal part. A cam 20 on the shaft 14 actuates a double armed lever 21 engaged with the shank 18, which parts are so arranged so that at properly timed intervals the shank, with the brush, is reciprocated, causing the brush 16 to sweep across the strip 2, at the place where the tab is to be applied. The inclined part of the shank, riding up and down the roller 19, causes the brush to rise out of the glue container before it sweeps across the strip, and to drop back into the container after applying glue to the strip.

The knife 13 is actuated by a cam or finger 22 on the shaft 14. Before the gear wheels 15 engage with the racks 15^a, for producing descent of the member 4, this finger 22 acts on an arm 23 fixed to the knife, and depresses the latter to effect the cut, the knife being then raised again by means of a spring 23^a.

The shaft 14 has fixed to it two arms 25 carrying rollers 26, and the member 4 has at its upper part two lateral projections or horns 24. When, after descent of the member 4, the gear wheels 15 are disengaged from the racks 15^a the rollers 26 act on the horns 24, and temporarily retain the member 4 in

its lowered position. Each of the horns 24 has an aperture, through which extends a lug 27 formed on the upper end of a rod 28. The rods 28 are elastically supported on the member 4, and move with same. The rods 28 are bent at their lower ends, to form horizontal arms arranged to strike rods 29 projecting from a vertically movable knife 30 guided in the frame 3, so that this knife is 10 depressed when the member 4 descends. The rollers 26 then act on the lugs 27, and impart further downward movement to the knife 30, which shears past the edge of the table 1, and cuts a sheet from the fly-paper strip 2. When the rollers 26 clear the lugs 15 27 and horns 24, the knife 30 is lifted by a spring 31, and the member 4 is also lifted by the springs 4^a.

The strip of paper 2 on the table 1 is held 20 fast by a lever 34, which has a flat arm 34^a extending partly across the table and lying on the strip; this arm is lifted at intervals by a cam 33 acting on the lever.

The sheet of paper cut from the strip 2 25 lies on one of a series of trays 32 mounted on endless conveyer chains 36 carried by sprocket wheels 39 fixed to shafts 37, 38. Rotation of these shafts moves the trays transversely of the direction of feed of the strip 2, and the trays are placed successively 30 in alinement with the table 1. The shaft 37 is connected by a train of gear wheels 40 to a ratchet wheel 41 engaged by a pawl 42 pivoted to a double armed lever 43. To 35 the latter is pivoted a rod 45, whereof the upper end lies in the path of a tappet on a wheel 44 driven by the shaft 14, so that depression of the rod 45 causes the ratchet wheel to rotate and impart through the gear 40 and shaft 37 a lateral movement to the tray on which the sheet has been deposited. The movement imparted to the tray somewhat exceeds the width of the strip 2, so that the sheet on the tray is moved 40 well out of the path of the strip.

An endless band 49 carrying two spring grippers 48 travels over two rollers 46, 47, the roller 46 being driven by a belt 200, from the shaft 14; the band 49 travels over 50 the series of trays, laterally of the path of the strip 2, and when the sheet is removed from the path of the strip, as described, one of these grippers is near the end of the table 1, under the frame 3. One tongue of the 55 gripper passes through a slot in the table 1, and comes to lie under the strip of paper. The other tongue has a tail, which travels along a curved guide 50, whereby the tongue is lifted, to lie over the strip, until the tail 60 clears the guide, whereupon the lifted tongue drops on to the strip, so that the latter is drawn on to the tray 32 now in line with the table 1. The gripper is opened, to release the strip, when the tail referred to 65 meets a curved guide 51 at the other end of

the tray. The flat arm of the lever 34 is lifted off the strip 2 by the cam 33 when the gripper seizes the strip, and is dropped on to the table 1 again when the forward feed of the strip is completed.

The gripper 48 deposits the end of the strip on two parallel guide wires 52, approximately at the level of the tray, and when the tray is shifted laterally, as described, after the cutting of the sheet from the strip, the sheet is guided by the said wires to two parallel rollers 53 having elastic bearings which allow them to move vertically. Between the rollers 53 lies a spindle 55 having a slot 54. The spindle 55 is axially movable and passes through a sleeve 57 rotatable in a frame part 56, and the rear end of the spindle is mounted in a bearing 58. To the sleeve is fixed a pinion 59 meshing with a large toothed wheel 61 fixed to a shaft 60 driven from the roller 47 by means of a train of gear wheels 62, 63, 64 so that the wheel 61 is driven by the main shaft 14 acting through the endless band 49. The pinion 59 is integral with a clutch member 65, and a spring 67 coiled on the spindle tends to hold a clutch member 66 fixed to the spindle in engagement with the clutch member 65, so that the spindle is rotated by the rotation of the pinion 59. The member 66 has a groove 68, within which is mounted a loose ring 69 having fixed to it a stud 70, and the latter projects into a slot 71 in a double armed lever 72, so that by rocking this lever the spindle 55 can be moved axially to disengage the clutch member 66 from the clutch member 65. The lever 72 is engaged with a bell-crank 74 pivoted at 73, and one arm of this bell-crank is bent, at 75, to form an inclined plane lying in the path 105 of a roller 76 carried by the wheel 61, so that in the course of each revolution of the wheel the bell-crank is rocked, rocks the lever 72, and thus temporarily disengages the clutch. The clutch is thrown into engagement again by the action of the spring 67, which pushes the spindle forward, and the forward movement of the spindle is timed so that the slot 54 engages the sheet which has been brought up to the rollers 53. The 110 spindle is then rotated, and the sheet is rolled thereon, under suitable pressure exerted by the elastically mounted rollers 53. When the spindle is drawn back by the lever 72, the roll of paper is stripped off it by the sleeve 57, and drops into a box or basket which is placed in position to receive it.

What I claim as my invention and desire to secure by Letters Patent of the United States is:

1. In apparatus for the purpose set forth, the combination of a feed table for a fly-paper strip, means for cutting tabs from a tab-strip, a vertically movable plate over said table adapted to engage tabs and apply 130

same to the fly-paper strip, means for cutting fly-papers from said fly-paper strip, trays for receiving said cut fly-papers, and means for intermittently moving said trays 5 transversely of the path of said fly-paper strip.

2. In apparatus for the purpose set forth the combination of a feed table for a fly-paper strip, means for applying adhesive to 10 equidistant portions of said strip, means for cutting tabs from a tab-strip, a vertically movable plate over said table adapted to engage cut tabs and apply same to said fly-paper strip at the parts coated by said adhesive applying means, means for cutting said fly-paper strip into sheets, trays for receiving said sheets, and means for intermittently moving said trays transversely of the path 15 of said fly-paper strip.

20 3. In apparatus for the purpose set forth the combination of a feed table for a fly-paper strip, means for applying adhesive to equidistant portions of said strip, means for applying tabs to said fly-paper strip at the 25 parts coated with said adhesive, means for cutting said fly-paper strip into sheets, and an intermittently moving conveyer whereby sheets cut from said fly-paper strip are removed transversely of the path of said fly- 30 paper strip.

4. In apparatus for the purpose set forth the combination of a feed table for a fly-paper strip, means for applying adhesive to equidistant portions of said strip, a fixed 35 plate, a movable plate having pins thereon, adapted to engage a tab-strip between said fixed plate and said movable plate, means for cutting from said tab strip a tab engaged between said plates, means for moving said movable plate toward said fly-paper strip and simultaneously rotating said plate, whereby the tab engaged with said plate is applied to said fly-paper strip, means for cutting sheets from said fly- 40 paper strip, and an intermittently moving conveyer whereby sheets cut from said strip are removed transversely of the path of said strip. 45

5. In apparatus for the purpose set forth 50 the combination of a feed table for a fly-paper strip, means for applying adhesive to equidistant portions of said strip, a fixed frame, a plate fixed to said frame above said table, a member slidable on said frame, a rotatable plate carried by said slidable member under said fixed plate, having pins thereon adapted to engage a tab between said fixed plate and said rotatable plate, means for reciprocating said slidable member between said fixed plate and said table, means whereby said rotatable plate is rotated in the course of its movement between said fixed plate and table, means for feeding a tab-strip between said fixed plate and said rotatable plate, and means for cutting said tab-strip when a portion thereof is between said plates, the 55 means for reciprocating said slidable member including a spring arranged to thrust said member from said table, a rack fixed to said slidable member, a mutilated toothed wheel intermittently coacting with said 60

and an intermittently moving conveyer whereby the sheets are removed transversely of the path of the strip.

6. In apparatus for the purpose set forth the combination of a table, an endless traveling band, grippers on said band, means whereby said grippers are alternately opened and closed in the course of the travel of said band, whereby said grippers intermittently engage and move a fly-paper strip 70 over said table, means for applying adhesive to equidistant portions of said fly-paper strip, means for applying tabs to said fly-paper strip at the parts coated by said adhesive applying means, and means for cutting said fly-paper strip into sheets. 75

7. In apparatus for the purpose set forth the combination of a table, an endless traveling band, grippers on said band, means whereby said grippers are alternately 80 opened and closed in the course of the travel of said band, whereby said grippers intermittently engage and move a fly-paper strip over said table, a lever arranged to bear on the fly-paper strip on said table, a cam which lifts said lever from said table when said grippers engage and move said fly-paper strip, means for applying adhesive to equidistant portions of said fly-paper strip, means for applying tabs to said fly- 85 paper strip at the parts coated by said adhesive applying means, and means for cutting said fly-paper strip into sheets. 90

8. In apparatus for the purpose set forth the combination of a feed table for a fly-paper strip, means for applying adhesive to portions of said strip, means for applying tabs to said fly-paper strip at the parts coated by said adhesive applying means, means for cutting said fly-paper strip into sheets, an intermittently moving chain-conveyer, and trays on said conveyer whereby sheets cut from said fly-paper strip are laterally removed from the path of said strip. 100 105

9. In apparatus for the purpose set forth the combination of a feed table for a fly-paper strip, means for applying adhesive to equidistant portions of said strip, a fixed frame, a plate fixed to said frame, a member slidable on said frame, a rotatable plate carried by said slidable member and having pins thereon, means for reciprocating said slidable member between said fixed plate and said table, means whereby said rotatable plate is rotated in the course of its movement between said fixed plate and table, means for feeding a tab-strip between said fixed plate and said rotatable plate, and means for cutting said tab-strip when a portion thereof is between said plates, the 110 means for reciprocating said slidable member including a spring arranged to thrust said member from said table, a rack fixed to said slidable member, a mutilated toothed wheel intermittently coacting with said 115 120

125 130

rack to move said member toward said table, a rotating arm, and a roller on said arm arranged to roll on said member after disengagement of said mutilated wheel from said rack.

In witness whereof I have signed this

specification in the presence of two witnesses.

OSKAR SÖRGEL.
